FIG. 12.

INVENTOR:

Harrison W. Bailey
By his attorney,
Charles S. Fooding.

UNITED STATES PATENT OFFICE.

HARRISON W. BAILEY, OF SOUTH BRAINTREE, MASSACHUSETTS.

TYPE FOR PRINTING TABULAR FORMS.

1,373,159.

Specification of Letters Patent.

Patented Mar. 29, 1921.

Application filed June 19, 1920. Serial No. 390,126.

To all whom it may concern:

Be it known that I, HARRISON W. BAILEY, a citizen of the United States, residing at South Braintree, in the county of Norfolk 5 and State of Massachusetts, have invented new and useful Improvements in Types for Printing Tabular Forms, of which the following is a specification.

In printing tabular forms it has been the 10 practice of printers heretofore to print the horizontal and vertical lines of the tabular form by means of small thin pieces of brass known as rules, the horizontal lines being printed by means of thin pieces of brass 15 known as cross rules and the vertical lines being printed by means of thin pieces of brass known as vertical rules or down rules.

In printing tabular forms by means of horizontal and vertical rules, the vertical 20 rules are usually of one piece, the length of the vertical line to be printed. This necessitates the use of short pieces of brass for the cross rules, the length of the pieces depending upon the distance between the 25 vertical rules. This distance between the vertical rules from line to line varies from six point (one-twelfth of an inch) or one-half pica upward.

In setting tabular forms, the rules are 30 positioned relatively to each other by means of quads, or quads and leads, and to obtain the different distances apart required for the lines necessitates the use of odd size quads, or quads and leads, or special contrivances.

35 It will be readily understood that to handle all these different rules, quads, leads and special contrivances necessitates the expenditure of a large amount of skilled labor in order to set the tabular form.

40 The object of this invention is to provide a printer's foundry type combining both the quad and rule in one character, said type to be of different sizes to give any required distance between the cross rules from six to 45 forty-eight point and cast in such sizes that with a combination of different types it will be possible to obtain any width column in one-half pica measures, it being understood that a pica is equal to one-sixth of an inch.

50 The tabular type of this invention may be designed for use with vertical rules and having on them characters corresponding to the horizontal rules only, in which case, the tabular type of this invention would 55 be used, when set up, with vertical rules.

The invention further contemplates a

tabular type in which only a character or characters corresponding to vertical rules are embodied, or said tabular type may embody characters for printing both the horizontal and the vertical rules, or the horizontal rules only.

To these ends the invention consists in a printer's foundry type with a printing character or characters thereon as hereinafter described and particularly as pointed out in the claims.

The invention further consists in the combination in a printer's form of a plurality of printer's foundry type with the characters 70 thereon extending from side to side, the printing faces of said characters combining to form a straight line in combination with vertical rules, whereby the horizontal and vertical lines of a tabular form may be 75 printed.

The invention further consists in the combination in a printer's form of a plurality of printer's foundry type having characters 80 extending across from one side to another oppositely disposed side of said type in a straight line and intersecting at right angles other characters extending from top to bottom on the face of the type, whereby continuous horizontal and vertical lines of 85 a tabular form may be printed.

Referring to the drawings:

Figure 1 illustrates a tabular form such as may be printed by the use of my improved tabular type in combination with 90 vertical rules.

Fig. 2 is a perspective view of a tabular type for printing horizontal lines in the tabular form and represents a tabular type of width equal to the six points or one-half 95 pica, which is known as the six set size being the unit set size for all body sizes.

Fig. 3 is a perspective view illustrating a tabular type with the position of the printing line corresponding to the horizontal rule 100 on an eighteen point body in standard line.

Fig. 4 is a perspective view of several of the tabular type shown in composition with vertical rules.

Fig. 5 is a perspective view of a tabular 105 type with a single vertical character thereon, this type being used for vertical rules in tabular work.

Fig. 6 is a perspective view of a tabular type with a pair of parallel vertical characters thereon, which is also used for vertical 110 rules in tabular work.

Figs. 7, 8 and 9 are perspective views showing special combination characters including both horizontal and vertical rules.

Figs. 10, 11 and 12 are perspective views 5 of tabular type of different designs having both horizontal and vertical characters thereon adapted to print horizontal and vertical lines.

Like numerals refer to like parts throughout the several views of the drawings.

In each of the different views of the drawings it will be understood that *a* and *b* are the oppositely disposed sides of the type; *c* is the bottom of the type; *d* is the top of the 15 type and *e* the printing face of the character on the type.

In the drawings, Fig. 2, 10 is the body portion of a type constructed in accordance with my invention and having a character 20 11 which extends entirely across the face of the type, being flush with the opposite sides of the body of the type. When a number of these types are placed side by side they will print the horizontal lines of a tabular 25 form the same as a continuous brass rule. These characters may also be placed one above another and when this is done the distance between rulings will be equal to the entire height of the body of the type, 30 that is, eighteen point type will give eighteen point rulings unless specially constructed for the use of headings.

It will also be understood that the line 35 printed by the face of the character 11 of the type will print on what is known as the standard line, that is, in line with the bottom of the letter in regular standard line foundry type, but may be so arranged as to print in any position desired between the top and 40 the bottom of the type.

It will be noted that the characters 11 are formed as an inverted V, whereby great strength is imparted to said characters as compared with that of the ordinary rule.

45 In Fig. 3, 12 is the body of the type and 13 is the character. This type illustrates an eighteen point body and the character is located thereon in standard line and is flush with the opposite sides of the body of the 50 type.

In Fig. 4 several type 14 with characters 55 15 thereon for printing horizontal lines are shown assembled with rules 16 for printing the vertical lines in a tabular form.

55 In Fig. 5 17 is the body of the type and 18 the character for printing a single vertical line.

In Fig. 6 19 is the body of the type and 20 and 21 the characters which print a pair 60 of parallel vertical lines.

In Fig. 7 22 is the body of the type, 23 and 24 are characters which will print vertical lines and 25 is a character which will print a horizontal line when the type is 65 set up.

In Fig. 8 27 is the body of the type, 28 is the character for printing the vertical line and 29 the character for printing the horizontal line.

In Fig. 9 30 is the body of the type, 31 70 75 76 the character for printing the vertical line and 32 and 33 are the characters which will print a pair of horizontal lines.

In Fig. 10 34 is the body portion of the type, 35 and 36 are characters for printing 75 a pair of vertical lines and 37 and 38 are characters for printing a pair of horizontal lines.

In Fig. 11 39 is the body of the type, 40 80 is the character for printing a single vertical line and 41 and 42 are the characters for printing a pair of horizontal parallel lines.

In Fig. 12 43 is the body of the type, 44 85 is a character for printing a horizontal line and 45 and 46 are characters for printing a pair of vertical lines.

It will thus be seen that any desired combination of horizontal and vertical lines may be printed by means of tabular type 90 embodying my invention and designed to fit different combinations and designs of tabular forms.

In the form of my invention illustrated in Figs. 2, 3 and 4, it will be understood that 95 the vertical rules 16 are to be used and the type prints the horizontal lines, but in the forms of my invention illustrated in Figs. 5 to 12 inclusive both the horizontal and vertical rules are omitted in setting up the type, 100 the type being set up face to face and when set up making a form which will print both horizontal and vertical lines of a tabular form without the use of the objectionable cross rules and vertical rules.

105 It will further be seen that where vertical rules are used, as in the printing of tabular forms illustrated in Fig. 1, there is a slight space between the horizontal lines and the vertical lines. This is necessarily the fact where separate vertical rules are employed 110 in combination with my improved type, but where the tabular type is of the character illustrated in Figs. 7, 8, 9, 10, 11 and 12 there is no space between the vertical and 115 the horizontal lines of the printed tabular form, these lines being continuous in the type, they will also be continuous in the printed tabular form and will intersect each other.

120 It will be understood that the printing face of the character, or the printing faces of the characters referred to in the following claims, contemplates any face now made in rules for printing tabular forms.

I claim:

1. In combination, a form for printing, comprising a plurality of printer's foundry type, each of said type having a printing character thereon, the printing face of said 130

- character extending from one side to the other of the body portion of said type, said type being arranged in series, and thin metal pieces or rules, interposed between adjacent types, the printing faces of said rules extending at right angles to the lines constituting the printing faces of said types, whereby a plurality of vertical lines may be printed with horizontal lines therebetween.
- 10 2. In combination, a form for printing, comprising a plurality of printer's foundry type, each of said type having a plurality of printing characters thereon, the printing faces of said characters extending in parallel lines from one side to the other of the body portion of said type whereby a plurality of uninterrupted straight parallel lines may be printed.
- 15 3. In combination, a form for printing,

comprising a plurality of printer's foundry type, each of said type consisting of a body portion and a plurality of printing characters thereon, the printing faces of said characters extending at right angles to each other and each of said faces extending from one side to the other of said body portion or from the top to the bottom thereof whereby a plurality of vertical lines may be printed with horizontal lines therebetween and intersecting said vertical lines.

In testimony whereof I have hereunto set my hand in presence of two subscribing witnesses.

HARRISON W. BAILEY.

Witnesses:

FRANKLIN E. LOW,
CHARLES S. GOODING.
